UNITED STATES PATENT OFFICE.

HERMAN AUGUST CASEY, OF DULUTH, MINNESOTA.

ELECTRODE-HOLDER.

1,400,418.

Specification of Letters Patent. Patented Dec. 13, 1921.

Application filed June 25, 1920. Serial No. 391,672.

To all whom it may concern:

Be it known that I, HERMAN AUGUST CASEY, a citizen of the United States, residing at the city of Duluth, in the county 5 of St. Louis and State of Minnesota, have invented new and useful Improvements in Electrode-Holders, of which the following is a specification.

This invention relates to the use of electric ovens such as are used in the manufacture of calcium carbid from coal and limestone. It has for its objects to provide means for insulating from heat the electric conductors used in such ovens and to effect a 10 saving in the electrodes used therein which constantly burn and wear off when in use and to facilitate the removal and replacement of the electrodes in such ovens when the same become worn and burned to such 15 an extent that the electric current conductors become too much exposed to the heat generated by the operation of the oven and the electrodes require replacing.

I attain these objects by the mechanism 20 illustrated in the accompanying drawings, in which:—

Figure 1 is a view of two of the electrodes showing in section the electric current conductors and the cooling mechanism, and the 25 means of holding the mechanism in position and Fig. 2 is a side view of Fig. 1.

Electrode blocks A and B are usually graphite blocks four inches square by sixteen inches long. C and D are similar 30 blocks four inches square and usually of lesser length. Electric current is supplied to electric current conductor E from which it passes through electric current conductors F and G to blocks A, B, C and D which 35 form one of the electrodes or a portion of one of the electrodes in an electric oven. The current then passes from A and B to similar electrodes separated from A and B by a short space thereby forming an electric 40 arc and producing the heat for the oven.

Electric current conductor E is fastened to and held in contact with electric current conductors F and G by bolt H.

50 Water jackets I, J and K are adapted to permit the continuous circulation of water through each of the water jackets to cool the adjacent parts and prevent the heat of the oven from melting or damaging the elec-

tric current conductors or other parts of the 55 mechanism.

An electric oven may contain any number of electrodes or pairs of electrodes such as are shown in Fig. 1. A similar number of electrode blocks such as A and B are contained in both upper and lower electrodes 60 of an electric oven.

Bolt L holds blocks A, B, C and D, water jackets I, J and K and electric current conductors F and G removably in position. 65 Bolt L passes through the center of blocks C and D.

Electrode block A is held in position by projection i which is a part of jacket 1 and which fits into notch a in block A. 70 Block B is similarly held in position by projection k and notch b.

In electric ovens of ordinary construction electrode blocks similar in size to blocks A and B are used and no blocks such as C and 75 D are used. The blocks in the ordinary oven are bolted in position in the same manner as block C and extend to a position indicated by dotted line M, no projections i and k or notches a and b are used.

The electrode blocks in electric ovens particularly the blocks in the upper electrode burn off and wear down very rapidly due to the intense heat and the presence of air and other combustible substances and the 80 electrodes require constant replacing.

With the ordinary ovens such replacement requires the removal of bolts L and the electrode blocks which have become worn down and burned off until the water jackets 90 and electric current conductors become exposed to too great heat from the oven and new blocks must be used.

To replace the electrode blocks in my invention it is merely necessary to loosen bolt 95 L and remove blocks A and B insert new blocks and tighten bolt L. A very great saving in labor is thereby accomplished.

The electrodes used in electric ovens are usually composed of graphite and are 100 very expensive. By the use of my invention a great saving is made in the number of electrodes used because whether blocks C and D, such as are used by me, are used or not, it is necessary to replace the old electrodes when they are burned or worn down to the point indicated by dotted line M. In 105 ordinary practice the portion of the elec-

trode wasted would be in length the distance from dotted line M to the top of block C whereas by my invention the portion wasted is only in length the distance from dotted line M to the bottom of block C.

Also in my invention because a much larger portion of the electrode may be used up before replacement is necessary, each electrode lasts much longer and it is not necessary to shut down and cool off an entire oven and replace electrodes so frequently as would otherwise be necessary thereby affecting a very great saving.

I claim:

1. In a mechanism of the kind described, a heat insulating block, an electrode and means for holding the heat insulating block and the electrode removably in position such means being adapted to release the

electrode upon loosening without releasing 20 the other parts of the mechanism.

2. In a mechanism of the kind described, a heat insulating block, an electrode and a bolt adapted to hold the heat insulating block and the electrode removably in position and adapted to release and permit the removal of the electrode upon the loosening of the bolt.

3. In a mechanism of the kind described, a heat insulating block adapted to serve as 30 a conductor of electricity from the electric current conductor to the electrode, an electrode and means for holding the heat insulating block and the electrode removably in position such means being adapted to 35 release the electrode without releasing the heat insulating block.

HERMAN AUGUST CASEY.
